FEED MECHANISM FOR WIRE BOUND BOX
BLANK MACHINES

David G. Kingsley, Mountain Lakes, N. J., assignor to Stapling Machine Co., Rockaway, N. J., a corporation of Delaware

Application November 27, 1946, Serial No. 712,711

6 Claims. (Cl. 1—8.3)

1

This invention relates to machines for making boxes, crates and parts thereof, and particularly to machines for securing binding wire to box or crate parts, to produce foldable box or crate blanks, or shooks, or parts therefor.

Among other objects, the invention provides an improved machine for making such box or crate blanks, or parts therefor; a machine that requires less attention by operators during operation; a machine that operates more easily on imperfect stock fed to the machine; a machine that requires less power consumption; and a machine that may be operated to produce greater output per hour.

Other objects will be in part obvious and in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings in which is shown one of the various possible embodiments of my invention:

Figure 1 is a top plan view partially diagrammatic of one embodiment of a box-making machine utilizing the invention;

Figure 2 is an enlarged fragmentary sectional view taken on the line 2—2 of Figure 1, showing box parts being conveyed and guided by mechanism embodying the invention;

Figure 3 is a side elevation of Figure 1 with certain parts broken away;

Figure 4 is an enlarged detailed top plan view of the delivery end of the machine of Figure 1, showing in more detail conveying and guiding mechanism embodying the invention, and showing driving mechanism for driving the conveying and guiding mechanism;

Figure 5 is an enlarged fragmentary side elevation of a portion of the machine shown in Figure 4;

Figure 6 is an enlarged top plan view of the receiving end of the machine of Figure 1; and

Figure 7 is an enlarged side elevation of the parts as shown in Figure 6.

Similar reference characters refer to similar parts throughout the various views of the drawings.

Box-making machine of the type in which the present invention is particularly useful, secure side sheets (or slats) to cleats together with a flexible binder (preferably wire), and join adjacent sets of such secured sheets and cleats together with the flexible binder in a continuous

2

operation to make folding box or crate blanks, or shooks, or to make parts such as ends or sides for such box or crate blanks. The cleats are usually re-sawed wood and serve to hold together, 5 space and reinforce the side sheets, which are made from veneer, fiber board, re-sawed lumber, or other suitable thin material sufficiently strong to carry the load for which the box or crate is designed. The wire binder reinforces the assembled box or crate and makes possible the use of the thin veneer side sheets. The cleats and side sheets are assembled on a moving conveyor and carried by the conveyor through suitable stapling mechanism that staples the sheets 10 to the cleats, and simultaneously staples the binding wire to the parts to secure them together, as well as to provide continuous circumferential binding around the completed box or crate. Also, the binding wire may be used to secure separate box parts together.

The width of the conveying mechanism and the stapling mechanism is adjustable so that the same machine may be adjusted to make wide box blanks or narrow box blanks, or box blanks of intermediate widths. The conveying mechanism and the operation of the stapling mechanism are adjustable to permit the assembly of cleats of different lengths and individual side sheets of different widths, and to permit different spacings of 15 the side sheets with respect to each other. Thus, such machines are useful to produce a wide variety of shapes of boxes, barrels, crates, shooks, etc. Such a box making machine is shown in detail in United States patent to A. L. Rosenmund No. 2,304,510, issued December 8, 1942.

Referring to the drawings, Figures 1 and 3, such a machine includes a cleat and side sheet assembly and conveying mechanism generally indicated by the section A. In this section the cleats *a* and the side sheets *b* are assembled on moving conveying belts *1* and *2*, in accordance with a prearranged order determined by spacing blocks *106* each having a cleat spacer element *c* and a side sheet spacing fin *d* carried by the conveyor belts *1* and *2*. The conveying mechanism conducts the cleats and side sheets thus assembled through stapling mechanism such as is described in the above-mentioned Rosenmund patent, but not shown in the present drawings, 20 which would occupy the section generally indicated by B. In this stapling section, wire strands are stapled to the parts as above described, and a continuous succession of finished box blanks are delivered from the section generally indicated by 25 C, each joined together by the wire binding which

is subsequently cut to isolate the box blanks one from the other.

In prior constructions of such box blank making machines, the ends of the side sheets and the outside sides of the cleats are guided by stationary side walls such as 17 (Figures 2 and 3), extending in a direction parallel to the movement of the conveyor belts 1 and 2. Because satisfactory production requires that the ends of the side sheets be aligned, the spacing between the stationary side guides can be only slightly greater than the lengths of the side sheets. In other words, relatively close adjustment of the stationary side guides with respect to the lengths of the side sheets has been required. Consequently, as the conveyor belts 1 and 2 carry the side sheets between the stationary side guides, there has always been the possibility of frictional drag between the side sheets and the stationary side guides. Such a drag, in some instances, may be unobjectionable, but if a side sheet for some reason such as warpage or the like becomes askew (i. e., moved to an oblique position with respect to the side guides) as the side sheet travels with the conveyor belt, then the frictional drag is materially increased. Because the side sheets may be of relatively thin wood veneer, if a side sheet gets so disarranged it may ride over the spacing block that is pushing it and so jam the machine. Such a condition most frequently arises when the veneer stock being used for the side sheets is warped or is cut incorrectly. Under such circumstances the operators feeding the side sheets to the moving conveyor belts and insuring their proper alignment on and movement with the conveyor belts 1 and 2, are forced to operate the machine at a slower rate, thereby reducing the normal capacity of the machine. That such a slower operation may be a real disadvantage is apparent when it is understood that a machine such as shown in the drawings is designed to operate to produce in the order of 500 wirebound orange crates an hour.

It is another object of the present invention to overcome such disadvantages and to provide a conveying construction which eliminates all frictional drag on the side sheets.

In the present embodiment these objects have been accomplished by providing oppositely disposed moving side walls against which the ends of the side sheets may abut, and which side walls travel at the identical speed of the conveyor belts 1 and 2.

Referring now to Figures 1 and 3, the right ends of the conveyor belts 1 and 2, viewing the machine as in the drawing, are supported by idler sprocket wheels 7 rotatably mounted on a shaft 100 the ends of which are supported in suitable bearings 101. The left ends of the belts 1 and 2 are supported by driving sprocket wheels 102 keyed to a drive shaft 36 journaled in bearings 103. Each conveyor belt is provided with holes 104 which mesh with studs 105 on the sprocket wheels, which studs serve in the case of the driving sprockets 102 to drive the belt, and also with regard to sprockets 7 and 102 to keep each belt in proper alignment. Secured to each conveyor belt are the aligned spacer blocks 106 having the spacing elements c and d (only several are shown) which serve two purposes—(1) as a pattern for the positioning of the sheets and cleats with reference to the conveyor belts, and (2) as a drive between the conveyor belts and the sheets and cleats. These spacer blocks are placed around the entire length of each conveyor belt and have

an arrangement peculiar to the particular style of box being manufactured. Thus the length of the conveyor belts and the spacing of the spacer blocks are selected so that if the belts were stretched out lengthwise they would provide for the assembly of a whole number of box blanks suitably and evenly spaced one from the other. To this end the conveyor belts are adjustable in length, and the spacing between the sprocket wheels 7 and the sprocket wheels 102 is adjustable by sliding the bearings 101 along supporting slides 107 at the receiving end of the machine.

Referring to Figure 2, adjacent the outside edge of each conveyor belt are horizontal bottom supports 108 on which the cleats slide while being carried forward by the spacer blocks to the stapling mechanism. The supports 108 are carried by angle supports 109 secured to framework 16 (Fig. 1). The side sheets rest on the cleats, and in this way the supported cleats and side sheets are moved forward by the spacing elements c and d of the blocks 106 carried by the conveyor belts 1 and 2. The conveyor belts themselves are held horizontal in driving position and kept from sagging out of a horizontal plane (Fig. 2) by angle supports 109 extending parallel beneath the conveyor belts, so that the blocks 106 and their spacer elements c and d are maintained in proper elevated driving position. The spacing between the opposing bottom supports 108 and the opposing stationary side wall guides 17 is adjustable, as is the spacing between the conveyor belts 1 and 2, to accommodate the length of the side sheets being assembled into box blanks. The driving sprocket wheels 102 for driving the belts 1 and 2 are driven through the medium of the shaft 36 and motor 20 in the following manner. Referring to Figures 1, 3, 4 and 5, the motor 20, located at the delivery end of the machine (Figures 1 and 4) through belts 21, drives a sprocket 24 keyed to clutch drum pulley 22 clutched to main drive shaft 23. The sprocket 24 through a chain drive 25 drives a sprocket 26 which, through suitable clutch mechanism, is engaged or disengaged from a shaft 27. When the clutch is in engaging position the driving sprocket 26 drives the shaft 27 which, through a train of gears 28, 29, 30 and 31, drives shaft 32 (Figures 4 and 5). To shaft 32 is keyed a drive sprocket 33 which, through a chain drive 34, drives a sprocket 35 keyed to the shaft 36, and this shaft imparts motion to the drive sprockets 102. This driving mechanism is fully described in the above-mentioned patent.

Also as fully described in the above-mentioned patent, the operation of the stapling mechanism is properly synchronized with the movement of the conveyor belts 1 and 2, with the spacing of the cleats, and with the spacing and widths of the side sheets, to drive the staples at proper points. To this end suitable clutch-operating mechanism is provided, as generally indicated at 110 (Figure 1), to start and stop the stapling mechanism.

Returning now to Figures 1 and 2, the need of holding the side sheets b and the cleats a in proper alignment as they pass to the stapling mechanism, has already been discussed. In order to overcome the problem that has previously existed, i. e. the drag between the side sheets and the stationary side guiding walls 17, it has been discovered that a thin vertically disposed belt placed between the stationary side guides and the side sheets b, and traveling at the identical speed of the conveyor belts 1 and 2, operates satisfac-

torily (1) properly to align the side sheets and the cleats and (2) to eliminate all frictional drags on the side sheets. With this construction the side sheets are supported and guided entirely by parts all moving at the same speed. In the present embodiment these traveling side walls comprise thin metal belts 3 which are sufficiently rigid to withstand the blows to which they may be subjected while the operators are assembling the cleats and side sheets on the moving conveyor belts 1 and 2, and are sufficiently strong to withstand the wear and tear to which the belts 3 may be subjected in continuous operation. I have discovered that such a metal belt may be supported on and driven by sprockets identical to and having the same axes as are used to support and drive the conveyor belts 1 and 2; and that by proper manipulation the metal belts may be turned through 90° as they pass from the sprockets at the receiving end, and held in this turned condition (i. e. in a vertical plane at 90° to the plane of the belts as supported by the sprockets) until they reach the sprockets at the delivery end. The belts thus turned are caused to travel along in contact with the stationary side guides 17 so that the belts 3 which now constitute moving side walls are effectively rigid in so far as any outward lateral movement is concerned, even though they are traveling forwardly with the conveyor belts 1 and 2.

To this end each belt 3 is supported at the receiving end of the machine on a sprocket 7, and at the delivery end on a sprocket 5, which sprockets are respectively carried by the shafts 100 and 36. As shown in Figure 3, each belt 3 in passing from its drive sprocket 5 rearwardly to its idling sprocket 7 is horizontally disposed. But as the belt leaves the idling sprocket 7, it is turned through 90°, as shown in Figures 1, 3, 6 and 7. The mechanism for thus turning each belt is constructed as follows: Two oppositely disposed rollers 13 and 13a are mounted to turn freely on vertical stud shafts 14 and 14a respectively. The shafts 14 and 14a are mounted on a rigid frame 15 secured with respect to the frame 16, which is part of the framework supporting the slide bars 107 which support the shaft 100. The belt 3 in leaving the sprocket 7 passes between the rollers 13 and 13a which turn the plane of the belt through 90°. The rollers 13 and 13a are so placed with reference to the periphery of the sprocket 7 that in imparting this quarter turn to the belt, a minimum of tensile and compression stresses are imparted to the belt; and yet they are positioned to bring the belt into vertical alignment with the side walls 17, the horizontal center lines of which lie above the two conveyor belts 1 and 2. This construction provides for utilizing sprocket wheels 7 which have the same diameter and axis as the sprocket wheels supporting the conveyor belts 1 and 2.

In addition to the guide rollers 13 and 13a, a third roller 13b is provided to guide each belt 3 into horizontal alignment with its stationary side wall 17, i. e. an alignment such that each belt 3 actually contacts and slides along its side wall 17. The roller 13b is supported on a stud shaft 14b supported from the frame 15. By utilizing such a third roller 13b the idler sprocket 7 may be conveniently spaced from the adjacent sprocket supporting the companion conveyor belt while at the same time permitting the turned belt 3 to be brought into the desired lateral spacing with respect to the adjacent conveyor belt as the two

travel together in conveying the cleats and side sheets to the stapling machine.

The rollers 13, 13a and 13b may be formed of steel or may be rubber covered to provide a resilient surface which effectively increases their diameters and thereby reduces the strains imparted to the belt 3 as it passes over the rollers. The receiving end of each stationary side guide 17 is preferably shaped as shown at 17a so that the belt 3 may move tangentially into contact with the side guide and thereby eliminate straining the belt 3 at the point where it moves into engagement with the side guide 17.

Referring now to the delivery end of the machine and particularly to Figures 1, 4 and 5, the side guide 17 extends through the stapling section B, and the belt 3 is maintained in its vertical guiding position to hold the cleats and side sheets aligned until after the stapling operation is completed. As shown in Figure 4, the side guide 17 ends at the point 17b, and the belt 3 leaves the end 17b and passes over a vertically disposed roller 9 mounted on a stud shaft 10. The periphery of the roller 9 is tangent to an extension of the supporting surface of the side 17 so that the belt 3, in passing from the point 17b of the side support 17, is not strained. As shown in Figure 5, the stud shaft 10 is supported on framework 11 made suitably rigid with respect to the stationary side guides 17, and to the base frame 12. In passing from the roller 9 the belt 3 is pulled over a vertically disposed stationary curved guide 9a opposite which is a vertically disposed roller 9b which is mounted on a stud shaft 10a. These two parts serve to move the belt 3 back into alignment with the sprockets 5 and 7, and also serve to spread the two belts 3 and to remove them from engagement with the now assembled box blank. This release of the box blank from the traveling side walls permits the box blank to travel forwardly independent of all conveyance, because simultaneously with the spreading of the side walls 3, the conveyors 1 and 2 (as shown in Figures 3 and 5), take a downward slope after passing through the stapling section B, to remove the spacer elements c and d from contact with the finished box blank. The conveyor belts are lowered by positioning the shaft 36 supporting the driving sprocket 102 in a plane below the shaft 100 supporting the rear idling sprockets.

The shaft 36 being placed below the shaft 100 places the top of drive sprocket 5 below the horizontal center line of belts 3 as they leave the side guides 17. Therefore, to avoid bending the belts 3 downwardly as they are turned 90° back into their normal planes, each belt 3 is first turned into its normal plane while running parallel to the center line of the side guides; and then after being turned, is caused to pass downwardly to engagement with the driving sprocket 5. The mechanism to accomplish this operation is as follows:

Each belt 3 (Figure 5) in passing from the roller 9b and the curved support 9a, passes over a curved horizontally disposed guiding surface 9c, suitably rigidly supported on a post 11a secured to the framework 12, in vertical and horizontal alignment with the belt as it is held between the part 9a and the roller 9b. A roller 9d mounted on a shaft 10b opposes the surface 9c and these two parts act to give the belt the required reverse quarter turn. The shaft 10b is supported on the post 11a. The belt in leaving the guide 9c passes downwardly to the drive sprocket 5, which is of

the same diameter as the drive sprockets 102 for conveyor belts 1 and 2.

The construction described has, among others, the advantages of using the same drive mechanism for both the conveyor belts 1 and 2 and the side wall belts 3, while at the same time permitting the belts to be driven at identical speeds.

Referring to Figure 1, the framework supporting the rollers at the receiving end of the machine which give the belt its quarter turn, and the framework supporting the rollers and guides that give the belt its reverse quarter turn are laterally adjustable so that the belts 3 together with the stationary side guides 17 and the driving and idling sprockets may be laterally adjusted to accommodate the mechanism to the desired length of side sheets being fabricated into box blanks. The belts 3 are adjustable in length, as are the conveyor belts 1 and 2, to accommodate the machine to the length of box blank being fabricated.

As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a box-making machine having a receiving end and a delivery end and stapling mechanism therebetween for securing together box parts assembled in longitudinal and lateral position, in combination, feeding mechanism for feeding assembled box parts to said stapling mechanism, said feeding mechanism including a plurality of moving endless conveyors extending from the receiving end to the delivery end, each conveyor being trained about members rotatable about axes located respectively at the receiving and delivery ends, spacer blocks secured to said endless conveyors for longitudinally spacing said box parts and for moving the same forwardly to said stapling mechanism, and two oppositely disposed endless side bands extending parallel to said conveyors, and each trained over members respectively rotatable about the said axes, said side bands serving to align the laterally positioned box parts laterally with respect to said conveyors and stapling mechanism as said box parts are moved forwardly to said stapling mechanism, and a drive driving said side bands at a speed identical to that of said conveyors.

2. In a box-making machine having a receiving end and a delivery end and stapling mechanism therebetween for securing together box parts positioned laterally and longitudinally, in combination, feeding mechanism for feeding assembled cleats and side sheets to said stapling mechanism, said feeding mechanism including a plurality of moving endless conveyors extending from the receiving end to the delivery end, each conveyor being trained about members rotatable about axes located respectively at the receiving and delivery ends, spacer blocks secured to said endless conveyor means for spacing said box parts and for moving the same forwardly to said stapling mechanism, and two oppositely disposed endless side bands extending parallel to said conveyors, and each trained over members respectively rotatable about the said axes for aligning said laterally positioned box parts laterally with respect to said conveyors and stapling mechanism as said box parts are moved forwardly to said stapling mechanism, means for driving said side bands at a speed identical to that of said

conveyors, and guides holding each side band in a plane perpendicular to the plane of said laterally positioned box parts as said side bands travel from the receiving end to the delivery end.

3. In box-making machinery having an assembly section for assembling in longitudinal and lateral positions box parts to be secured together, a securing section for securing the box parts, and a delivery section for delivering the assembled and secured parts, in combination, feeding means for properly locating said box parts in the assembly section and for moving the assembled parts to said securing section and to said delivery section, said feeding means including two moving spaced parallel endless conveyors each of which is trained over a front sprocket at the assembly section and a rear sprocket at the delivery section supported respectively on a front shaft and a rear shaft whereby the two upper turns of the conveyors move forwardly at the same speed past said three sections and carry forwardly the assembled box parts, and two moving side walls respectively extending parallel to and outside of said upper turns for laterally aligning the laterally positioned box parts with respect to said assembly and securing sections, said moving side walls comprising two metal bands each trained over front and rear sprockets of the same diameter as the front and rear sprockets supporting said conveyor means and respectively supported on said front and rear axes, and a drive for driving one of said shafts to impart the identical speed to said conveyors and to said two metal bands.

4. In box-making machinery having an assembly section for assembling in longitudinal and lateral positions box parts to be secured together, a securing section for securing the parts, and a delivery section for delivering the assembled and secured parts, in combination, feeding means for properly locating said box parts in the assembly section and for moving the assembled parts to said securing section and to said delivery section, said feeding means including two moving spaced parallel endless conveyors each of which is trained over a front sprocket at the assembly section and a rear sprocket at the delivery section rotatable respectively about a front axis and a rear axis whereby the two upper turns of the conveyors move forwardly at the same speed past said three sections and carry forwardly the assembled box parts, and two moving side walls respectively extending parallel to and outside of said upper turns for laterally aligning said laterally positioned box parts with respect to said assembly and securing sections, a drive driving said moving side walls at a speed identical to that of said conveyor means, said moving side walls comprising two metal bands each trained over front and rear sprockets of the same diameter as those supporting said conveyors and respectively supported on said front and rear axes, forward guides for giving each metal band a quarter turn as it leaves its front sprocket, and rearward guides giving each metal band a reverse quarter turn as it approaches the rear sprocket, whereby each metal band is held in a plane at right angles to the said front and rear axes and broadside to said laterally positioned box parts as it travels forwardly to the securing section.

5. In box-making machinery having an assembly section for assembling longitudinally and laterally arranged box parts to be secured together, a securing section for securing the box

parts, and a delivery section for delivering the assembled and secured parts, in combination, feeding means for properly locating said box parts in the assembly section and for moving the assembled parts to said securing section and to said delivery section, said feeding means including two moving spaced parallel endless conveyors each of which is trained over a front sprocket at the assembly section and a rear sprocket at the delivery section rotatable respectively about a front axis and a rear axis whereby the two upper turns of the conveyors move forwardly at the same speed past said three sections and carry forwardly the assembled box parts, and two moving side walls respectively extending parallel to and outside of said upper turns for laterally aligning said laterally arranged box parts with respect to said assembly and securing sections, a drive driving said moving side walls at a speed identical to that of said conveyors, said moving side walls comprising two metal bands each trained over front and rear sprockets of the same diameter as those supporting said conveyors and respectively supported on said front and rear axes, forward guides giving each metal band a quarter turn as it leaves its front sprocket, rearward guides giving each metal band a reverse quarter turn as it approaches the rear sprocket, whereby each metal band is held in a plane at right angles to the said front and rear axes and broadside to said laterally arranged box parts as they travel forwardly to the securing section, and intermediate guides for guiding and backing each metal band as it travels forwardly in its quarter turned condition.

6. In box-making machinery having an assembly section for assembling longitudinally and laterally arranged box parts to be secured together, a securing section for securing the box parts and a delivery section for delivering the assembled and secured parts, in combination, feeding means for properly locating said box parts in the assembly section and for moving the assembled parts to said securing section and to said

delivery section, said feeding means including two moving spaced parallel endless conveyors each of which is trained over a front sprocket at the assembly section and a rear sprocket at the delivery section rotatable respectively about a front axis and a rear axis whereby the two upper turns of the conveyors move forwardly at the same speed past said three sections and carry forwardly the assembled box parts, and two moving side walls respectively extending parallel to and outside of said upper turns for laterally aligning said laterally arranged box parts with respect to said assembly and securing sections, a drive driving said moving side walls at a speed identical to that of said conveyors, said moving side walls comprising two metal bands each trained over front and rear sprockets of the same diameter as those supporting said conveyors and respectively supported on said front and rear axes, forward guides giving each metal band a quarter turn as it leaves its front sprocket, rearward guides giving each metal band a reverse quarter turn as it approaches its rear sprocket, whereby each metal band is held in a plane at right angles to the said front and rear axes and broad side to said laterally arranged box parts as they travel forwardly to the securing section, and intermediate guides guiding each belt band after it has received its quarter turn inwardly into the desired aligning side wall position, and guiding each belt outwardly away from the side sheets at the delivery section before the said rearward guides impart the reverse quarter turn.

DAVID. G. KINGSLEY.
